(57) CLAIM

I claim the ornamental design for a crown of a golf club head, as shown and described.

DESCRIPTION

FIG. 1 is a rear, top perspective view of a crown of a golf club head of the present design;

FIG. 2 is a top view of the golf club head of FIG. 1;

FIG. 3 is a rear view of the golf club head of FIG. 1;

FIG. 4 is a heel-end side view of the golf club head of FIG. 1; and,

FIG. 5 is a toe-end side view of the golf club head of FIG. 1.

The ornamental design that is claimed is shown in solid lines in the drawings. The broken (dashed) lines shown in FIGS. 1 through 5 are included only for the purpose of illustrating environmental elements, and form no part of the claimed design.
